UNITED STATES PATENT OFFICE.

DAVID A. MIDDLETON, OF LOGANSPORT, INDIANA.

BINDER FOR TABLETS.

1,071,562.

Specification of Letters Patent.

Patented Aug. 26, 1913.

Application filed March 19, 1912. Serial No. 684,865.

To all whom it may concern:

Be it known that I, DAVID A. MIDDLETON, a citizen of the United States, residing at Logansport, in the county of Cass, State of Indiana, have invented certain new and useful Improvements in Binders for Tablets; and I do declare the following to be a full, clear, and exact description of the invention, such as will enable others skilled in the art 10 to which it pertains to make and use the same.

My invention relates to improvements in binders for tablets and more especially for use with tablets composed of loose leaves.

15 It has for its object to provide a binder in which a single sheet of paper or a number of sheets of paper will always lie flat and enable the entire surface to be written upon.

It also has for its object to provide a 20 binder with means by which the sheets of paper may be reversed and both sides used to write upon.

It further has for its object to provide a binder which can be converted from a two 25 cover or double board binder into a single cover or board binder.

It further has for its object to provide a binder which is simple, inexpensive and durable in construction, easy to manipulate 30 and very attractive in appearance.

It further has for its object to provide a binder in which it is possible to remove the top sheet without disturbing the other sheets.

35 It still further has for its object to provide a binder in which the sheets of paper are held securely in position and at the same time are capable of being moved easily and quickly which is especially desirable when 40 being used by stenographers or other rapid writers.

The invention consists in the construction, combination and arrangement of the several parts as more fully hereinafter described 45 and claimed.

Referring to the drawings: Figure 1 is a top plan view of the binder with one portion of the cover thrown back and the sheets of paper exposed ready for use. Fig. 2 a side 50 view with the cover closed. Fig. 3 a sectional view on the line $x-x$ of Fig. 1, on an enlarged scale. Fig. 4 a sectional view on the line $y-y$ of Fig. 1, on an enlarged scale. Fig. 5 a detail perspective view of 55 the pivoted member of the binder. Fig. 6 a detail bottom plan view of the base plate of

the binder. Fig. 7 a detail view of the spacing plate.

In the drawings in which like numerals of reference denote like parts throughout the several views; 1 represents the cover of the 60 binder which comprises upper and lower portions 2 and 3 respectively, and a back portion 4. The back portion of the cover is hinged to the upper and lower portions 65 by means of hinges made of cloth or other suitable material. The base plate 5 of the binder is secured to the back of the cover by metal eyelets 6. The upper edge of the base plate 5 is turned under the said plate and 70 forms a flange 7, extending preferably the entire length of the plate, and recesses 8 are formed in the upper edge of the base plate. The lower edge 8a of the base plate 5 is cut away at 9 at each end and bent 75 under said plate to form a flange 10.

The pivoted member 11 of the binder is made of resilient spring wire, preferably in one piece, and comprises a middle portion 12, which is pivoted in the flange 10 on the 80 lower edge of the base plate 5, and arched portions 13 at each end of the middle portion, each of said arched portions being provided with a rearwardly extending lug 14 designed to pass through the recesses 8 85 of the base plate, this action being permitted by reason of the spring action of the pivoted member 11. The flange 7 serves as an abutment for the lugs 14 of the arches 13. By having the lugs 14 of the arched portions 90 fastened below the upper surface of the base plate all obstructions or projections are 95 eliminated and in consequence the leaves of the tablet will always lie perfectly flat at all times.

A plate 15 is provided between the back of the binder and the under surface of the base plate which is seated in the flanges 7 and 10 and serves to reinforce the base plate and also space it from the back of the 100 binder, said plate being provided with notches 16 in its upper edge for the purpose of allowing sufficient space for the operation of the lugs of the pivoted member. The lower edge 17 of the plate 15 serves to retain the middle portion of the pivoted member in place in the flange 10. The eyelets 6 also pass through the plate 15 and hold it securely in place. The leaves 18 of the tablet are provided with suitable perforations 110 19 to receive the arched portions of the pivoted member.

When it is desired to convert the binder into a single board binder the upper portion 2 of the cover can be turned backward on its hinge and caused to lie flat against the 5 under surface of the lower portion 3 of the cover. To insert the leaves of the tablet in the binder the arched portions 13 are pulled upward until the lugs 14 are released from the recesses 8 of the base plate 5, the piv- 10 oted member is then turned downward on its pivot and the arched portions are inserted in the perforations 19 of the leaves of the binder, then the arched portions are turned upward and downward and passed 15 through the recesses 8 and sprung under the plate 5 when the tablet is ready for use.

I do not desire to be understood as limiting myself to the specific details of constructions and arrangement as herein described 20 and illustrated, as it is manifest that variations and modifications may be made in the features of construction and arrangement in the adaptation of the device to various conditions of use without departing from the spirit and scope of my invention and improvements. I therefore reserve the right 25 to all such variations and modifications as properly fall within the scope of my invention and the terms of the following claims.

30 What I claim is:—

1. In a binder for tablets, a plate having flanges on opposite edges and recesses adjacent one edge, a backing for said plate, a spring binding member pivotally mounted 35 between the plate and the flange on one of its edges and provided with arches having lugs adapted to pass through said recesses and engage the flange on the other edge of said plate and a plate interposed between 40 the first mentioned plate and the flanges thereof with its rear edge engaging the middle portion of the spring binding member

and holding it between the plate and the flange and preventing lateral movement thereof, substantially as described. 45

2. In a binder for tablets, a plate having flanges on opposite edges and recesses extending through one edge, a backing for said plate, a spring binding member pivotally mounted between the plate and the flange 50 on one of its edges and provided with arches having inwardly extending lugs adapted to pass through said recesses and engage said plate and a plate, interposed between the first mentioned plate and the flanges thereof, 55 having notches in which the lugs of the arches are received and one of its edges engaging the middle portion of the pivoted member and preventing lateral movement thereof, substantially as described. 60

3. In a binder for tablets, a plate having flanges on opposite edges and recesses extending through one edge, above the flange thereof, and cut-away portions on the other edge, a backing for said plate, a spring binding member pivotally mounted between said plate and the flange on one of its edges and extending upward through said cut-away portions and provided with arches having inwardly extending lugs adapted to pass 70 through said recesses, engage said plate and abut against the flange below said recesses and a plate interposed between the first mentioned plate and the flanges thereof one of its edges engaging the middle portion of the 75 binding member and preventing lateral movement thereof, substantially as described.

In testimony whereof I affix my signature in the presence of two witnesses.

DAVID A. MIDDLETON.
